UNITED STATES PATENT OFFICE.

JOHN P. POMEROY, OF GREAT BARRINGTON, AND HENRY M. VAN DEUSEN,
OF WESTFIELD, MASSACHUSETTS.

DESIGN FOR A WHIP-LOAD.

SPECIFICATION forming part of Design No. 31,468, dated August 29, 1899.

Application filed July 29, 1899. Serial No. 725,642. Term of patent 14 years.

To all whom it may concern:

Be it known that we, JOHN P. POMEROY, residing at Great Barrington, in the county of Berkshire, and HENRY M. VAN DEUSEN, residing at Westfield, in the county of Hampden, State of Massachusetts, have invented and produced a new and original Design for Whip-Loads, of which the following is a specification.

Our invention relates to a new and original design for a whip-load; and the leading feature consists in the peculiar configuration given to the same.

In the accompanying drawings, Figure 1 is an elevation of a whip-load constructed according to our design. Fig. 2 is a central longitudinal section of the same.

In the said drawings the reference-numeral 1 designates the load, consisting of the shank

2, having a peripheral groove 3 near one end, 20 and of a cylindrical head 4, also formed with a peripheral groove 5 near one end. This head is larger than the shank, forming a shoulder 6 at its junction with the shank, which is slightly beveled, as shown more clearly in 25 Fig. 2.

Having thus described our invention, what we claim is—

The design for a whip-load, substantially as herein shown and described.

In testimony whereof we have hereunto set our hands in presence of two subscribing witnesses.

JOHN P. POMEROY.
HENRY M. VAN DEUSEN.

Witnesses:

HAROLD P. MOSELEY,
D. W. STEVENS.
